Primary Examiner — Ruth McInroy(74) *Attorney, Agent, or Firm* — Skaar Ulbrich Macari, P.A.(57) **CLAIM**

We claim the ornamental design for a cap, as shown and described.

DESCRIPTION

FIG. 1 is a side view of a cap showing our new design;
 FIG. 2 is a front view thereof.
 FIG. 3 is a back view thereof.
 FIG. 4 is a top view thereof; and,
 FIG. 5 is a bottom view thereof.
 The details shown in broken lines form no part of the claimed design.
